US00D930726S

(12) **United States Design Patent** (10) Patent No.: **US D930,726 S**
(45) Date of Patent: **** Sep. 14, 2021**

(54) **ROBOT**

(71) Applicant: **RN Chidakashi Technologies Private Limited**, Mumbai (IN)

(72) Inventors: **Sneh Vaswani**, Mumbai (IN); **Prashant Iyengar**, Mumbai (IN); **Chintan Raikar**, Mumbai (IN)

(73) Assignee: **RN Chidakashi Technologies Private Limited**, Mumbai (IN)

(**) Term: **15 Years**

(21) Appl. No.: **29/724,109**

(22) Filed: **Feb. 12, 2020**

(51) LOC (13) Cl. **15-99**

(52) U.S. Cl.

USPC **D15/199**

(58) **Field of Classification Search**

USPC D15/199; D21/578-583, 621, 622; D32/21

CPC B25J 5/007; B60B 19/006; B62D 57/024; H01F 7/0221; Y10S 901/01
